UNITED STATES PATENT OFFICE.

JENS ANDERSON, OF CHICAGO, ILLINOIS, ASSIGNOR TO ENTERPRISE RAILWAY EQUIPMENT COMPANY, OF CHICAGO, ILLINOIS.

INTERCHANGEABLE BALLAST GONDOLA PLOW-CAR.

1,172,246.

Specification of Letters Patent. Patented Feb. 22, 1916.

Application filed September 2, 1915. Serial No. 48,601.

To all whom it may concern:

Be it known that I, JENS ANDERSON, a citizen of the United States, residing at Chicago, in the county of Cook and State 5 of Illinois, have invented a certain new and useful Improvement in Interchangeable Ballast Gondola Plow-Cars, of which the following is a full, clear, concise, and exact description, reference being had to the accompanying drawings, forming a part of this specification.

This invention relates to improvements in interchangeable ballast gondola plow car.

One object of the invention is to provide an interchangeable car of the type above indicated so arranged that certain sections of the floor, when the car is being used as a gondola or plow car, are adapted to be positioned vertically to form the end walls of the car when the latter is being used as a ballast or hopper car.

Another object of the invention is to provide a car of the interchangeable type above indicated so arranged that the load, when the car is being used as a ballast car, is distributed over a greater length of the car than has hitherto been customary and thereby decreasing the concentration of the load.

The invention furthermore consists in the parts and devices and novel combination of the parts and devices as herein shown, described and claimed.

In the drawing forming a part of this specification, Figure 1 is a horizontal sectional view of a portion of the car, the section being taken just above the floor line of the car, the upper half of the figure illustrating the arrangement of the parts when the car is being used as a gondola or plow car, and the lower half of the figure illustrating the arrangement of the parts when the car is being used as a ballast car. Fig. 2 is a longitudinal sectional view taken substantially on the line 2—2 of Fig. 1, parts being broken away in order to prevent crowding of the drawing. Fig. 3 is a vertical sectional view, illustrating more particularly the arrangement of the flooring when the car is being used as a gondola or plow car, the section being substantially on the line 3—3 of Fig. 1. Fig. 4 is a transverse vertical sectional view taken substantially on the broken line 4—4 of Fig. 1,

and Fig. 5 is a view similar to Fig. 4 but 55 taken on the broken line 5—5 of Fig. 1.

In said drawing, the car as shown is provided with a built-up box-like center sill, 10, side sills or girders 11—11, bolsters 12, fixed or permanent end floor sections 13, end 60 sills 14, side posts 15—15, upper longitudinally extending members or rails 16—16 secured to the tops of the posts, narrow fixed side boards 17—17 extending longitudinally of the car beneath the rails 16, 65 and side dumping doors 18—18 extending full length of the car, said doors being pivoted along their upper edges to the fixed boards 17 as indicated at 19—19. The doors 18 are held in their closed position 70 by means of straps 20 secured to the lower edges of said doors, each of said straps being provided with a loop 21 with which cooperates a keeper or latch 22, the keepers 22 being mounted on longitudinally extending operating shafts 23—23 on each side of the car. The shafts 23 may be operated by any suitable mechanism at the ends of the car as will be understood.

Each car is provided with a hopper section intermediate the trucks, each hopper section comprising a plurality of longitudinally extending hoppers A—A, each hopper having a center dump hinged door 24, the latter being pivoted along their upper 80 edges to hinge butts 25 secured to the center sill as clearly illustrated in Figs. 4 and 5. Any suitable mechanism may be employed for operating the doors 24, the operating shafts for said doors being located 85 as indicated in section at 26—26. At the ends nearest the ends of the car, the hoppers A are provided with vertical hopper sheets 27 which are located below the center sill and with inclined hopper sheets 28 90 which extend from the tops of the hopper sheets 27 up to the floor level of the car and to points above the inner wheels of the trucks, as clearly indicated in Fig. 2. When the car is being used as a ballast or hopper car, the bottoms of the hoppers A are formed by floor sections 29—29, the latter having their lower edges resting upon longitudinally extending Z bars 30, and their upper edges resting against the side sills or girders 11—11. When the car is being used as a flat bottom gondola or plow car, said floor sections occupy the position indicated 95 100 105

most clearly in the right hand portion of Fig. 4 and the top of Fig. 1, said floor sections 29 then resting along their inner edges on top of the center sill 10 and along their outer edges on angle irons 130 secured to the tops of the side sills 11. The interchangeable hopper bottoms-floor sections 29 are of such length that they extend between the vertical hopper sheets 27 and vertical 5 hopper sheets (not shown) at the opposite ends of the hoppers A, when the sections 29 form the bottoms of the hoppers. It will also be apparent that said sections 29 when forming a portion of the floor cover 10 those portions of the hoppers A for which said sections form the bottoms thereof.

Those portions of the hoppers A at the ends which are designated as A' in Figs. 1 and 2, and which have the inclined sheets 20 28 for the bottoms thereof, are covered by pivoted floor sections 31 which extend from side to side of the car, said sections 31 being pivoted along their outer or lower edges (depending upon the position of the sections 31) 25 as indicated at 32-32. Said floor sections 31, when in horizontal position, complete the flooring of the car between the permanent end floors 13 and the floor sections 29 when the car is being used as a flat bottom gondola or 30 plow car, as clearly indicated in Figs. 1 and 3. Each pivoted section 31 consists of a plurality of transversely extending boards suitably secured by U-shaped plates 33 at the ends thereof as indicated in Fig. 1 and 35 are braced by means of angle irons 34 secured at intervals thereon on the under side, when said members occupy a horizontal position. When the car is employed as a ballast car, said pivoted floor sections 31 40 are adapted to be moved to a vertical position as indicated most clearly in Fig. 2 and in this position they form the end walls of the car when it is used as a ballast car. To retain the sections 31 in vertical position, 45 I have provided slidable bolts or latches 35 at the upper edges thereof, which latches or bolts are adapted to have their ends inserted in the suitable holes 36 (see Fig. 4) formed in the fixed side walls 17, the latter 50 having secured thereto plates 37 through which the latches 35 extend, to thereby provide a more permanent construction.

In order to maintain the proper level of the car floor covered by the floor sections 29, 55 I have provided central and side longitudinally extending floor boards 38 and 39 mounted on the center and side sills respectively. (See Figs. 1 and 4.)

From the preceding description, it will 60 be seen that I have provided a car which may be readily adapted for any one of a number of different services, and furthermore, the arrangement is such, that a minimum number of parts are employed there- 65 by decreasing not only the first cost but

the dead weight of the car. Another important advantage of my improvement resides in the fact that by employing the pivoted floor-end wall sections 31, the hoppers can be extended to points over the truck 70 wheels thereby distributing the ballast load over a greater area, increasing the ballast carrying capacity and minimizing the concentration of the load. As will be understood by those skilled in the art, the hinged 75 side dumping doors 18-18 adapt the car for plow service in the usual manner, when the pivoted floor sections 31 and floor sections 29 are arranged in horizontal position.

Although I have herein shown and de- 80 scribed what I now consider the preferred embodiment of my invention, the same is merely illustrative and I contemplate all changes and modifications as come within the scope of the claims appended hereto. 85

I claim—

1. In an interchangeable plow, hopper ballast car and having fixed end floors and a central hopper section, pivoted floor sections at the ends of the hoppers, said floor 90 sections in horizontal position forming a portion of the floor over the ends of the hoppers and, in vertical position, forming the entire, vertical end walls of the car when the latter is being used as a ballast 95 car, whereby when said pivoted floor sections are in horizontal position over the ends of the hoppers, a plow may be moved lengthwise of the car throughout its entire length. 100

2. In an interchangeable plow, hopper ballast car having fixed end floor portions and an intermediate hopper section, the end portions of the hoppers extending up to points over the inner wheels of the trucks, 105 movable sections adapted to form the floor portions over said end portions of the hoppers when in horizontal position, said members being movable to a vertical position above said inner wheels of the trucks to 110 thereby form the complete, vertical end walls of the car when the same is being used as a ballast car, whereby when said pivoted floor sections are in horizontal position over the ends of the hoppers, a plow 115 may be moved lengthwise of the car throughout its entire length.

3. An interchangeable flat bottom gondola ballast car having fixed end floor portions and a hopper section intermediate the 120 trucks, the hopper section comprising a plurality of longitudinally extending hoppers, the ends of said hoppers adjacent the ends of the car being provided with upwardly and outwardly inclined hopper bottom sheets extending to points above the inner wheels of the trucks, and floor sections extending transversely of the car and pivoted along their outer edges adjacent the inner edges of said fixed floor sections, said 125 130 135

pivoted floor sections when in horizontal position covering only those portions of the hoppers above said inclined hopper bottom sheets, and in vertical position forming 5 the end walls of the car when the latter is being used as a ballast car, whereby when said pivoted floor sections are in vertical position to form the end walls of the car the load is concentrated entirely between 10 said end walls.

4. In a car of the character described, the combination with a car body provided with pivoted side doors, hopper section intermediate the trucks, each hopper having a center dump hopper door, permanent end floor sections, and pivoted floor sections adapted 15 to cover portions of said hoppers when in horizontal position, the remainder of the car floor between said pivoted floor sections 20 being formed by floor sections bodily displaceable from a horizontal position over the hoppers to an inclined position within the hoppers to form the bottoms thereof.

5. In a car of the character described, 25 the combination with a car body provided with pivoted side doors and a hopper section intermediate the trucks, said car having

means for forming the floor thereof when the same is used as a flat bottom gondola or plow car, said means consisting of fixed 20 floor sections, pivoted floor sections, and bodily displaceable floor sections, said pivoted and bodily displaceable floor sections covering the hopper section when said pivoted and displaceable floor sections are in 25 horizontal position.

6. In a car of the character described having a hopper section intermediate the trucks, means for forming the floor of the car when same is used as a flat bottom gondola or plow car, said means consisting of fixed 40 floor sections, pivoted floor sections, and bodily displaceable floor sections, said pivoted and bodily displaceable floor sections, when in horizontal position, covering 45 the hopper section, the displaceable floor sections being shiftable to a position below the floor level to thereby form the hopper bottoms.

In witness that I claim the foregoing I 50 have hereunto subscribed my name this 13th day of August, 1915.

JENS ANDERSON.
